Edward B Bradley
Inventor

United States Patent Office.

EDWARD B. BRADLEY, OF NEW HAVEN, CONNECTICUT.

Design No. 3,605, dated August 10, 1869.

DESIGN FOR A PICTURE-FRAME.

The Schedule referred to in these Letters Patent and making part of the same.

To all whom it may concern:

Be it known that I, EDWARD B. BRADLEY, of New Haven, in the county of New Haven, and State of Connecticut, have invented a new Design for Picture-Frame; and I do hereby declare the following, when taken in connection with the accompanying drawings, and the letters of reference marked thereon, to be a full, clear, and exact description of the same, and which said drawings constitute part of this specification, and represent, in—

Figure 1, a front view, and in

Figure 2, a sectional view.

This invention relates more particularly to a design for small wood frames, but is alike applicable to other and larger frames; and

The design consists in forming, in the body of the frame, a plain recessed band of gold.

In order to the better understanding of my inven-

tion, I will describe the same as illustrated in the accompanying drawings.

A is the frame proper.

B, the rabbet.

In the surface of the frame I form a groove, a, into which I place a strip, d, which fills the groove that has been previously gilded, and so that the gilded surface of the said strip will sink below the surface of the frame.

What I claim as my invention, and desire to secure by Letters Patent, is—

The herein-described design for picture-frames, consisting of the recessed plain gilt band d in the body of the frame.

EDWARD B. BRADLEY.
